UNITED STATES PATENT OFFICE.

HARVEY K. ERNSBERGER, OF NORWALK, OHIO.

WATER-HEATER.

No. 874,316.

Specification of Letters Patent.

Patented Dec. 17, 1907.

Application filed April 10, 1907. Serial No. 367,319.

To all whom it may concern:

Be it known that I, HARVEY K. ERNSBERGER, a citizen of the United States, residing at Norwalk, in the county of Huron and 5 State of Ohio, have invented a new and useful Water-Heater, of which the following is a specification.

This invention relates to water heaters and its object is to provide simple, compact and 10 efficient means whereby the temperature of water within the heater may be quickly raised by the use of a minimum amount of fuel.

A still further object is to provide means 15 whereby a large percentage of heat heretofore wasted is utilized for raising the temperature of the water.

A still further object is to provide a novel arrangement of tubes capable of expanding 20 or contracting without danger of injury to any of the parts, said tubes being disposed in such a manner as to present a large heating surface to the hot products of combustion.

25 Another object is to provide deflecting means whereby the products of combustion can be directed or spread laterally among the tubes prior to the escape of the hot products from the heater.

30 With these and other objects in view the invention consists of certain novel features of construction and combinations of parts which will be hereinafter more fully described and pointed out in the claims.

35 In the accompanying drawings is shown the preferred form of the invention.

In said drawings: Figure 1 is a detail view 40 of the header and some of the pipes of the heater, the same being removed from the jacket or casing; and Fig. 2 is a longitudinal section through the heater.

Referring to the figures by characters of reference, 1 designates a header constituting one wall of the heater and sub-divided by a 45 partition 2 into a cold water compartment 3 and a hot water compartment 4. A feed pipe 5 opens into the cold water compartment at a desired point and return pipes 6 also open into said compartment. Outflow 50 pipes 7 extend from the upper portion of the hot water compartment and it will be noted by referring to Fig. 2 that said compartment laps the upper end of the cold water compartment so as to permit the pipes 7 to extend upward from the top of the header 1.

Formed within the inner face of the header 1

are openings 8 disposed in staggered relation adjacent the sides and top of the header. Secured within each of these openings is a return tube 9 having a cap 10 secured upon its free end for closing the same and each of these tubes opens into the hot water compartment 4. All of the tubes are preferably parallel and form an arch extending along the sides and over the top of the fire box 11 65 of the heater.

A series of openings 12 similar to the openings 8 are formed within the inner face of the header 1 adjacent, and along a line parallel with, the bottom of said header, and secured 70 within each of these openings is a return tube 13 similar to the tubes 9 and having a cap 14 at its free end constituting a closure therefor. These tubes 13 form the grate of the heater and each tube opens into the hot water compartment 4. A faucet 15 is preferably connected to the free end of one of the tubes 13 and by means thereof hot water may be drawn from the heater for domestic purposes.

The partition 2 is formed with a plurality 80 of openings 16 each of which is disposed in alignment with the center of one of the openings 8 and 12. Secured within each opening 16 is one end of a pipe 17 which extends longitudinally within the center of the adjoining 85 tube 9 or 13 and terminates at a point removed from the cap thereof. It will thus be seen that the pipes 17 serve to convey cold water from the compartment 3 to the closed ends of the tubes 9 and 13 from which it returns through said tubes to the compartment 4. A deflecting plate 18 is preferably secured within the casing 19 of the heater and between certain of the tubes 9 for the purpose of spreading the products of combustion 95 prior to their escape through the outlet flue 20.

It is of course obvious that when water is admitted to the compartment 3 and the entire system filled the water contained within 100 the various tubes and flues will be quickly heated by the products of combustion within the fire box 11. A circulation will thus be established and the cold water will be conveyed from compartment 3 to the closed 105 ends of tubes 9 and 13 and will then return to compartment 4 through said tubes. During this return flow the water will contact with surfaces which are directly heated by the products of combustion and the water while 110 returning to the header will heat the pipes 17 and raise the temperature of the cold water

therein before the same is discharged into the tubes. Owing to the efficient circulation which is thus established it becomes impossible for the tubes to become overheated.

5 By providing certain of the tubes and pipes for use as a grate the heat which is usually wasted at this point and which ordinarily results in the burning out of grates of the ordinary construction can be practically entirely 19 used for heating the water.

It will be seen that this heater is very compact and durable in construction and the parts thereof can not readily get out of order. The arrangement of tubes disclosed presents 15 an extensive heating surface to the products of combustion and inasmuch as these tubes extend entirely around the fire box, and as the hot water compartment 4 is disposed directly at one end of said compartment the 20 temperature of the water can be quickly raised and the amount of fuel necessary to obtain efficient results is reduced to the minimum.

What is claimed is:
25 In a heater the combination with a header

comprising a hot water compartment and a cold water compartment; of a plurality of return tubes communicating with and extending from the hot water compartment, a closure upon the free end of each tube, a return pipe extending from the cold water compartment and into each tube, said pipes being disposed to discharge water into the tubes adjacent their closures, certain of said tubes being disposed in a horizontal plane to 35 constitute a grate and the remaining tubes being disposed along curved lines extending from the sides and over the grate, and a deflecting plate interposed between the grate tubes and the tubes thereabove for directing 40 products of combustion laterally among the tubes.

In testimony that I claim the foregoing as my own, I have hereto affixed my signature in the presence of two witnesses.

HARVEY K. ERNSBERGER.
